UNITED STATES PATENT OFFICE.

CHARLES LINFIELD, OF LOGAN, UTAH.

CABINET IRONING-BOARD.

1,134,394.

Specification of Letters Patent. Patented Apr. 6, 1915.

Application filed July 14, 1914. Serial No. 350,951.

To all whom it may concern:

Be it known that I, CHARLES LINFIELD, a citizen of the United States, residing at Logan, in the county of Cache and State of Utah, have invented a new and useful Cabinet Ironing-Board, of which the following is a specification.

The invention relates to improvements in cabinet ironing boards.

10 The object of the present invention is to improve the construction of cabinet ironing boards and to provide a simple and inexpensive device of this character, adapted to present the appearance of a neat and attractive article of furniture, and equipped with an ironing board and a sleeve board adapted to be easily and quickly arranged for use and readily returned to their folded or closed position.

20 With these and other objects in view the invention consists in the construction and novel combination of parts hereinafter fully described, illustrated in the accompanying drawings, and pointed out in the claims hereto appended, it being understood that various changes in the form, proportion, size and minor details of construction, within the scope of the claims, may be resorted to without departing from the spirit or 25 sacrificing any of the advantages of the invention.

In the drawings:—Figure 1 is a perspective view of a cabinet ironing board constructed in accordance with this invention, the ironing board being arranged for use. Fig. 2 is a similar view, the ironing board being arranged in its closed or folded position. Fig. 3 is a central vertical sectional view of the cabinet ironing board, the parts being arranged as shown in Fig. 1. Fig. 4 is a central vertical sectional view of the cabinet ironing board, parts being arranged as illustrated in Fig. 2. Fig. 5 is a horizontal sectional view, the parts being arranged as shown in Fig. 3. Fig. 6 is a horizontal sectional view showing another form of locking device for retaining the ironing board in position for use.

Like numerals of reference designate corresponding parts in all the figures of the drawings.

In the accompanying drawings, in which is illustrated the preferred embodiment of the invention, 1 designates a cabinet open at the front and comprising in its construction vertical side walls 2 and horizontal top and

bottom walls 3 and 4, arranged between and suitably secured to the vertical side walls. The cabinet is provided at the top with an attaching board or member 5, secured in recesses of the vertical side walls and having its rear face arranged in flush relation with the rear edges of the said side walls 2 to enable the cabinet to fit flat against a wall. The top attaching board or member 5 projects laterally from the cabinet and its terminal projecting portions 6 are pierced by screws or other suitable fastening devices for securing the cabinet in place against a wall or the like. The cabinet is provided at 70 its lower portion with a horizontal partition 7 spaced from the bottom 4 to form a compartment 8 for containing sad irons and other articles.

The open front of the cabinet is adapted 75 to receive an ironing board 9, which constitutes a closure for the cabinet and the latter is provided at its upper portion with downwardly tapered braces 10 having upwardly inclined inner edges and forming a 80 tapering space to receive the outer or upper portion of the ironing board, which is tapered in the usual manner. The ironing board is provided at its inner end with a transverse cleat or bar 12, designed to be 85 constructed of hard wood or other suitable material, and having laterally projecting rounded terminals 13 for operating in inclined guides or ways 14 of the cabinet. The guides or ways 14 are preferably formed 90 by spaced strips or bars secured to the inner faces of the vertical side walls 2 of the cabinet and the said guides or ways, which extend upwardly and rearwardly, are provided at their upper ends with horizontal 95 branches 15, preferably formed by recesses and adapted to receive the lateral projections 13 of the ironing board, whereby the inner end of the latter is supported when the ironing board is arranged for use. By 100 extending the guides or ways downwardly and forwardly, the lower end of the ironing board is brought to a position at the front of the cabinet in the folding or closing movement of the said ironing board.

105 The ironing board, when arranged in a horizontal position, is supported by inclined bracing bars or members 16, hinged at their lower ends 17 to the bottom of the cabinet and also hinged at their upper ends 18 to 110 the lower or outer face of the ironing board at opposite sides thereof and at a point in

termiate of the ends of the same. The inclined braces or members 16 are adapted to swing inwardly and outwardly and they fold against the outer face of the ironing board when the latter is returned to its closed or folded position. When the ironing board is closed or folded, it is arranged in a vertical position between the side walls of the cabinet, in flush relation with the front edges thereof, and it is secured in such position by a top catch 19.

When it is desired to arrange the ironing board for use, its upper end is unfastened and it is swung downwardly and outwardly, carrying with it the hinged braces 16, which also form a fulcrum on which the ironing board is adapted to swing in raising its lower end to a horizontal position. In the outward movement of the ironing board the lower or inner end thereof is guided by the inclined ways and when the lateral projections 13 reach the upper ends of the ways, the ironing board is drawn outwardly to carry the said projections 13 into the horizontal branches or extensions 15. The ironing board is locked in such extended position by an inclined gravity catch 20 secured at its upper edge to a transverse bar or member 21 by hinges 22, and extending downwardly and forwardly and adapted to automatically engage a transverse bar or cleat 23 secured to the upper face of the ironing board near the rear end thereof, and constituting a keeper to coact with the gravity catch. The inner or rear edge of the keeper cleat or bar is beveled and receives the lower inclined edge of the gravity catch 20 when the ironing board is drawn outwardly. When the ironing board is locked in its extended position by the gravity catch, it is rigidly supported and securely held against accidental folding. The gravity catch is adapted to be lifted out of engagement with the keeper bar or cleat to permit the ironing board to be folded.

Various other locking devices may, of course, be employed for securing the ironing board in its extended position, and in Fig. 6 of the drawings are shown pivoted catches 24, mounted upon the inner or rear portions of the ironing board and adapted to be turned into and out of engagement with the blocks or pieces in which are formed the horizontal branches or extensions of the guides or ways. The catches 24 are pivoted intermediate of their ends and are adapted to be readily swung into and out of engagement with the fixed portions of the cabinet.

The cabinet ironing board is equipped with a sleeve board 25, connected at its inner end with the transverse bar or member 21 by a hinge 26 which permits the sleeve board to be swung upwardly and downwardly to fold the sleeve board within the cabinet and

to arrange the said sleeve board in a horizontal position above the ironing board. The sleeve board is provided intermediate of its ends with a lug or support 27, secured to the lower face of the sleeve board and preferably braced by a block or piece 28, as clearly illustrated in Fig. 3 of the drawings. The sleeve board is retained in its folded position within the cabinet by means of a pivoted button 29, mounted on the transverse bar or member 21 at the front face thereof and adapted to be readily turned into and out of engagement with the sleeve board. When the sleeve board is arranged in a horizontal position for use, the ironing board forms a firm support for the same.

The cabinet is provided at the front of the compartment 8 with a door 30 hinged at its lower edge to the bottom 4 of the cabinet at the front edge thereof and provided at its upper free edge with a catch 31, which secures the door of the horizontal partition 7. The door is of a width to extend across the space between the hinged braces 16, which, with the said door, form a closure for the compartment 8. The partition 7 has an extended front portion 32 and is provided at the ends thereof with recesses 33. The extended portion fits against the upper free edge of the door 30 and the recesses 33 receive the hinged braces when the latter are in a vertical position.

In practice, the ironing board will be provided with the usual padding or covering, and it has a marginal recess arranged at the inner face of the ironing board and extending along the sides and across the outer end to enable the covering to be attached to the ironing board at the side edges without interfering with the folding of the ironing board within the open front of the cabinet. When the ironing board is in its folded or closed position, the padding or covering is arranged within the cabinet and is protected by the same.

What is claimed is:—

1. A device of the class described including a cabinet provided at opposite sides with upwardly extending guides or ways, an ironing board having its inner or lower end engaged with and slideable upwardly and downwardly in the said ways, a brace hinged at its lower end to the cabinet and at its upper end to the ironing board and supporting the outer portion thereof when the ironing board is arranged in an extended position, and a catch mounted in the cabinet and arranged to lock the ironing board in its extended position.

2. A device of the class described including a cabinet open at the front and provided at opposite sides with upwardly extending ways having approximately horizontal branches at their upper terminals, an ironing board provided with projecting means

slidable upwardly and downwardly in the said ways and movable into the said branches for supporting the inner end of the ironing board, a catch for locking the ironing board in engagement with the said branches, and means for supporting the outer portion of the ironing board.

3. A device of the class described including a cabinet provided at opposite sides with upwardly extending ways having approximately horizontal branches extending forwardly from the upper terminals of the ways, an ironing board having projecting means slidable in the said ways and movable outwardly into the branches thereof for supporting the inner end of the ironing board, a gravity catch mounted within the cabinet and arranged to automatically engage the ironing board for locking the same against inward or rearward movement, and means for supporting the outer portion of the ironing board.

4. A device of the class described including a cabinet provided with upwardly extending ways having approximately horizontal branches, an ironing board provided with projecting means slidable in the ways and movable into the said branches, a keeper carried by the ironing board, and an inclined gravity catch hinged at its upper edge and having its lower edge arranged in the path of the keeper and adapted to automatically engage the same when the ironing board is moved to an extended position, and means for supporting the outer portion of the ironing board.

In testimony, that I claim the foregoing as my own, I have hereto affixed my signature in the presence of two witnesses.
